CAR COOLING DEVICE

Walter C. Phillips, San Francisco, Calif., assignor
to Phillips Refrigeration Products, Inc., San
Francisco, Calif., a corporation of California

Application September 17, 1932, Serial No. 633,602

5 Claims. (Cl. 98—6)

My invention relates to means for assisting in depressing the temperature in refrigerator cars charged with cargo, and is of the general type of mechanism disclosed in my copending application entitled "Car cooler", Serial No. 569,479, filed October 17, 1931, now Patent No. 2,019,796, patented November 5, 1935, and my copending application entitled "Apparatus and method for precooling cars", Serial No. 594,043, filed February 19, 1932, now Patent No. 1,965,802, patented July 10, 1934.

I have found through considerable experience with such devices that not only are the internal dimensions of the so-called standard refrigerator car variable within several inches, but have also found that the height of the bulkhead or bunker wall which extends from a point above the floor of the car to a point adjacent the ceiling or roof of the car and separates the load compartment from the ice bunker varies considerably in height, and consequently affords an upper bunker opening varying considerably in size. Furthermore, I have found that while with some commodities it is the custom to load only to a moderate height from the floor, with other commodities it is the custom to load the car to a point closely approaching the top of the bunker wall, and therefore leaving only a relatively small space between the top of the load and the roof of the car.

30 It is therefore an object of my invention to provide a car cooling device which is particularly useful in connection with refrigerator cars which are to be loaded a maximum amount.

Another object of my invention is to provide a 35 car cooling device which can be utilized in refrigerator cars of varying dimensions.

A further object of my invention is to provide a car cooling device in which short circuiting of cool air from the upper bunker opening directly through the load to the lower bunker opening is minimized.

An additional object of my invention is to provide a car cooling device in which air leakage is inhibited despite variations in refrigerator car size.

The foregoing and other objects are attained in the embodiment of the invention shown in the drawings, in which

50 Figure 1 is a cross section of the upper portion of a refrigerator car on a transverse vertical plane, showing the car cooling device of my invention mounted therein.

Figure 2 is a cross section, the plane of which 55 is indicated by the lines 2—2 of Figure 1.

Figure 3 is a cross section, the plane of which is indicated by the lines 3—3 of Figure 1.

Figure 4 is a partial plan of the mechanism shown in Figure 1.

Figure 5 is a view similar to Figure 1 but with 5 the air circulating units omitted.

In its preferred form, the car cooling device of my invention is for use in a refrigerator car having a bunker wall dividing the car into a load compartment and an ice bunker, and terminating short of the roof of the car to afford an upper bunker opening, and includes a member extending transversely of the car adjacent the opening and serving as a support for a plurality of air circulating units which are transversely movable along the support and can be clamped in position thereon. Each of the units preferably includes a housing arranged substantially horizontally adjacent the roof of the car and is provided with an air circulating fan therein and with vanes for deflecting air discharged by the fan toward the roof of the load compartment of the car.

As indicated particularly in Figures 1 and 3, the car cooling device of my invention is installed in a standard refrigerator car which includes side 25 walls 6 and 7 as well as a roof 8. An exterior roof 9 spans the car and a bunker wall 11 extends from a point spaced from the floor of the car, not shown, and terminates short of the roof 8 to provide an upper bunker opening 12. The bunker wall 11 divides the car into an ice bunker 13 and a load compartment 14 in which the cargo is stowed with its upper limit substantially at the load line 16 indicated in Figure 3.

As disclosed in my copending applications above identified, air is preferably circulated from the ice bunker 13 wherein ice, not shown, is held in place by a screen 17, through the upper bunker 12 into the load compartment 14 of the car, from whence the air passes through the load and back to the bottom of the bunker 13. In accordance with the present invention, I preferably span the load compartment 14 of the car with a support member 18 which extends transversely of the car between the walls 6 and 7. In order to alter the length of the member 18 to accord with varying widths of cars, and in order to clamp or support the member 18 in place, at one end of the beam 18 I preferably provide a screw 19 terminating in a spike head 20 adapted to engage the material of the wall 6.

At the other end of the beam 18 I preferably provide a similar screw mechanism 21 adapted to engage the wall 7 upon operation of a toggle lever 55

22. In order further to brace the beam 18 adjacent its middle, I preferably afford a spiked rod 23 pivotally engaging as at 24 the lower flange of the beam, and reinforced by a stay 26 pivotally engaging as at 27 the upper flange of the beam 18. When the beam is mounted, the spike 23 is swung from a position nested between the flanges of the beam and enters the material of the bunker wall 11 as indicated in Figure 3. A very strong support against lateral deflection is thus provided. The beam 18 in addition carries a strip of deformable or flexible material 28 which is adapted to abut the bunker wall 11 when the beam 18 is positioned adjacent thereto in order 10 to inhibit leakage between the beam and the bunker wall, and between the beam and the car walls 6 and 7.

In accordance with the present invention, there are preferably mounted on the beam 18 a plurality of air circulating units such as 31 and 32. Since in the present instance two such units are utilized, and since the units are substantially identical, I shall describe but one of them. It is to be understood that any suitable number of such units can be utilized in accordance with the space available for them. Each unit preferably includes a lower angle member 33 adapted to overlie one edge of the beam 18 and to be received in clips 34 fastened on the beam 18. Extending 20 from the angle 33 are uprights 36 and 37 carrying toggle levers 38 terminating in spike blocks 39 designed to engage the roof 8 of the car upon suitable manipulation of the toggle levers, and thereby to hold the members in place between the beam 18 and the roof 8 of the car. The members 36 and 37 at their upper extremities are joined by an angle 41 which, except for transverse strips 42 and 43, completes the framework. Preferably sheet material extends between the 25 members of the framework forming therewith what may be termed a "plate" to prevent flow of air, and in addition flexible material for sealing is fastened to the member 41 as at 46, is similarly fastened to the member 31 as at 47, and particularly is fastened to the member 36 as at 48.

By the provision of the two units 31 and 32, the units can not only be easily brought into position on the beam 18 but can be transversely shifted with varying amounts of overlap of the 30 sealing strip 48 on the unit 31 in order to accommodate for variations in transverse dimension of the car in which the units are used. Each unit preferably includes also a Venturi section 49 preferably of sheet metal and fastened to the framework, and carrying a generally horizontal cylindrical extension 51 of sheet metal which is disposed above the load line 16 and immediately under the roof 8 of the car. The extension 51 35 communicates with the Venturi section 49 and consequently affords a path of egress for air from the ice bunker 13 through the upper bunker opening 12 and the Venturi section 49 to the interior of the load compartment 14. Disposed within 40 the extension 51 is a bracket 52 carrying an electric motor 53 arranged with its shaft substantially horizontal and at its forward end carrying an air circulating fan 54.

I have found through numerous experiments 45 and tests that with mechanism as so far described, the cool air discharged by the fan 54 tends to short-circuit and return immediately to the lower bunker opening. Therefore I provide a plurality of deflecting vanes 56 and 57 which extend across 50 the forward portion of the extension 51 in the

path of air discharged by the fan 54. The deflecting vanes 56 and 57 are inclined upwardly so that a portion of the air discharged from the fan is directed toward the roof 8 of the car, and does not and cannot immediately short-circuit 5 through the load back to the ice bunker. Since only a portion of the air discharged by the fan, however, is so deflected, some of the air does so short-circuit and is effective to cool the load immediately in front of and below the fan unit, 10 whereas that portion of the deflected air which is directed toward the roof of the car flows approximately to the center of the car and then circulates through the load and back beneath the floor of the car to the ice compartment 13. 15

With the arrangement as described, not only is thorough circulation provided, but there is afforded an even distribution of air which is effective to produce a uniform cooling of the load which is essential to the success of such mechanisms. Furthermore, the device is sufficiently compact to be practical in a car in which the load extends entirely up to the load line and furthermore is capable of orientation in various cars to accommodate for variations in dimensions therein. 20

It is to be understood that I do not limit myself to the form of car cooling device shown and described herein, as the invention as set forth in the following claims may be embodied in a plurality of forms.

I claim:

1. A car cooling device for use in refrigerator cars of varying transverse dimension and having an upper bunker opening comprising a support adapted to extend transversely of said car adjacent said opening, a plurality of demountable air circulating units mounted on and movable along said support for individual positioning in said car, and deformable means for inhibiting air leakage between said units and said car and between said units themselves.

2. A car cooling device for use in refrigerator cars of varying transverse dimension and having an upper bunker opening comprising a support adapted to extend transversely of said car adjacent said opening, a plurality of demountable air circulating units mounted on and individually movable along said support, means for clamping said units in selected position on said support, and means for inhibiting air leakage around said units in any selected position thereof.

3. A car cooling device for use in refrigerator cars of varying transverse dimension and having an upper bunker opening comprising a support adapted to extend transversely of said car adjacent said opening, a plurality of demountable air circulating units mounted on and individually movable on said support to vary the spacing between said units themselves and said car, means for clamping said units in any selected position on said support, and flexible sealing strips mounted on said units and adapted to close the spaces between said units and said car and between said units themselves in all selected positions of said units on said support.

4. A car cooling device for use in successive refrigerator cars having upper bunker openings of different widths, comprising a demountable air circulating unit including a plate, means for holding said unit in position with said plate overlying part of said opening, plate means overlying part of said opening from adjacent an edge of said unit to a wall of said car, and sealing means to preclude leakage of air between the edges of said plate and said plate means.

5. A car cooling device for use in successive refrigerator cars having upper bunker openings of different widths, comprising a demountable air circulating unit including a plate, means for holding said unit in position with said plate overlying part of said opening, plate means overlying part of said opening and extending from a wall of said

car to a point different distances from the edge of said plate in different cars, and sealing means spanning the distance between said plate means and said plate to preclude leakage of air therebetween.

WALTER C. PHILLIPS.
